UNITED STATES PATENT OFFICE.

RALPH H. DICK, OF MARIETTA, OHIO, AND PETER W. WIGGINTON, OF RAHWAY, NEW JERSEY, ASSIGNEES TO THE SAFE-CABINET COMPANY, OF MARIETTA, OHIO, A CORPORATION OF OHIO.

DOOR FOR SAFES OR CABINETS.

1,329,511.

Specification of Letters Patent.

Patented Feb. 3, 1920.

Application filed May 8, 1918. Serial No. 233,277.

To all whom it may concern:

Be it known that we, RALPH H. DICK and PETER W. WIGGINTON, both citizens of the United States, and residents, respectively, of 5 Marietta, Washington county, Ohio, and Rahway, Union county, New Jersey, have invented a certain new and useful Improvement in Doors for Safes or Cabinets, of which the following is a specification.

10 Our invention relates to doors intended for use on cabinets or light weight safes used as containers for valuable records, documents and similar articles and is designed especially to prevent the entrance of 15 heat to the interior of the safe or cabinet and to furnish an additional safe-guard to the contents thereof in case in a fire, the exterior front of the safe or cabinet should be destroyed or damaged, either by a long continued period of excessively high temperature 20 or by a fall resulting from the giving way of the floors of the building in which the safe or cabinet is located.

We accomplish this by using a door constructed in a manner and of materials which will resist the entrance of heat to the interior of the cabinet or safe with an especial regard to circumventing such entrance of 25 high temperatures along the lines of the structure where the materials having the greatest heat conductivity are located. The details of the construction are shown in the drawings herewith of a preferred form and described in the following specification:—

30 Solid metal doors are open to the objection that they constitute good conductors of heat, and we have also found in our experiments and tests that by insulating any and all metal parts which might constitute lines 35 of heat communication from the exterior to the interior of the safe or cabinet, a much greater safety to the contents is assured.

In the drawings herewith:—

Figure 1 is a horizontal section through 40 the safe-cabinet taken on a plane as of line 1—1 of Fig. 2.

Fig. 2 is a vertical sectional view through the door and front part of the safe-cabinet taken on a plane indicated by the line 2—2 45 of Fig. 1.

Fig. 3 is a perspective view showing one of the catches which hold the two parts of the door together.

Fig. 4 is a perspective view showing the method of connecting the bolt levers together.

As shown herewith 10 indicates the outer walls of the safe or cabinet and 11—11 are the inner walls which surround the space within which the various papers, documents, etc., are contained. Between the outer walls 10 and 11, in the space 12 any of the usual forms of insulation may be employed. While our construction can be used on either single or double doors, we show here double doors in which 13 is the outer front wall, 14 the inner wall, with hinges 15—15 and handles 16—16 intended to operate the bolt rods 17—17 which in turn move the locking bolts 18—18.

As shown the door consists of sheet metal shaped to form the outer walls with angular projections as at 19 which fit closely into corresponding spaces in the jamb of the cabinet or safe, thereby providing a broken 75 or tortuous channel to delay the entrance of heat through the openings at the hinges. At 20—20, on either side of the door, this metal wall is bent inwardly and ends at the point 21—21, a heat insulating material 22—22 serving to form the walls surrounding a dead air space 23 extending laterally across the door structure.

The same principle is applied at the points 24—24 where the doors interlock when 80 closed, a tortuous channel being provided and the metal walls ending at the points 25—25.

The dead air space 23 acts to break definitely all heat conductivity lines from the 85 exterior of the safe or cabinet through the door structure to the interior. The metal in the walls 19—19 and 24—24, in the handles 16—16; and in the combination lock (not shown) either ends or is parted 90 at the point of this air space. Any heat conducted from the exterior by any of these metal parts to the air space 23 would naturally be absorbed or distributed throughout this air space the surrounding walls of 100 which are almost entirely of an insulating material of low conductivity.

In actual practice an excessively high temperature sometimes occurs at a particular spot at the exterior of the safe or cabinet and this may result in the weakening 105

or breaking down of the insulating material adjacent to that particular spot, which would permit the heat to proceed toward the interior of the safe or cabinet. The air 5 space 23 would serve in a case of this kind to take up and distribute this excessive heat instead of compelling the insulation directly between the interior and the weakened spot to bear the whole load.

10 The insulating material 22 may be of any of the known types and may be of either a dry nature or constituted so that under a high temperature, moisture in the form of vapor may be given off to reduce the temperature and wet down the contents of the 15 interior of the safe or cabinet.

To secure the inner part of the door to the outer part, we use the small catches 26-26 of any usual form. They should be 20 of sufficient strength to stand any ordinary strain but light enough in construction to allow the outer or front part of the door to separate from the inner section, if by a fall or in any other manner the front section 25 should be thrown out of its normal position.

The locking device, comprising the handles 16-16, bolt rods 17-17 and bolts 18-18, also serves from the nature of its construction to permit of this separation of the 30 two sections, as, while when the two sections are secured together by the catches 26-26, the double bolts 18-18, operated by the handles 16-16 and the rods 17-17, engage with the frame of the safe or cabinet to 35 hold the outer and inner door sections in their proper respective positions, if the outer section should move outwardly from the inner section the bolts 18-18 in the inner section will remain in position and

will be detached from the rods 17-17 at 40 the point 27-27.

It will thus be seen from the foregoing description that in this door for safes or cabinets there is no metal line of heat conductivity from the exterior to the interior 45 that is not broken by insulation and a dead air space. In addition if an insulation material containing chemically bound moisture is used, the vapor released under high temperatures would flow freely into the air 50 space 23 where it would equalize and consume the heat that might enter.

As stated above we show in the drawings herewith a preferred form of our invention, but we do not desire to be limited strictly 55 thereto, as the principle involved can be adapted to single doors and other modifications may be made without departing from the spirit or scope thereof.

We claim:—

A door for a fire-heat resisting document-preserving cabinet or safe comprising an inner member composed of a sheet metal casing and a slab of non-conducting material set therein, an outer member composed 65 of a sheet metal casing and a slab of non-conducting material set therein, and connecting means between said members holding them in spaced relation, the non-conducting slab portions being exposed opposite 70 each other and said connecting means being attached thereto.
